UNITED STATES PATENT OFFICE

CASIMIR WRONA, OF UGINE, FRANCE

ROTARY PUMP

Application filed August 15, 1929, Serial No. 386,099, and in Luxemburg, September 8, 1928.

My invention relates to rotary pumps and concerns more particularly an embodiment involving an improvement in that type of machine known as a paddle pump.

5 The objects of my invention will be obvious to those skilled in the art in the following description when taken in connection with the accompanying drawing forming part of this specification and in which—

10 Fig. 1 is a vertical transverse section through my improved pump;

Fig. 2 is a longitudinal section taken therethrough;

15 Fig. 3 is a side elevational view of a paddle;

Fig. 4 is a front elevational view thereof;

Fig. 5 is a plan view thereof;

16 Fig. 6 is an elevational view of a plate detail;

20 Fig. 7 is a transverse sectional view of said plate;

Fig. 8 is a section taken through a ring;

25 Fig. 9 is a front elevational view of said ring;

26 Figs. 10 to 13 are fragmentary elevational views illustrating the operation of my device; and

Fig. 14 is a section through a flow control arrangement.

30 Referring to the drawing more in detail, in a stator *a* is locked a ring *b* by any suitable means such as a pair of keys. Said ring *b* is adapted to receive two plates sliding into dove-tailed slots provided in said ring all of 35 which will hereinafter be described more in detail.

36 A rotor *d* is provided with four radial slots *d*⁰ adapted to receive four paddles *e*. The diameter of said rotor is made such with respect to the internal diameter of the ring *b* 40 that there exists between the said rotor and the ring *b* an annular space *b*⁰.

I provide in the stator *a*, the ring *b* and the plates *c*, inlet and outlet openings respectively receiving inlet conduit *A* and outlet conduit *R*.

I provide the stator *a* with two cheeks or flanges *a*¹ and *a*² secured thereto by any suitable means such as nuts and bolts as shown.

50 I dispose springs *f* each in a recess *d*⁰ pro-

vided in the bottom of the slots *d*⁰ of rotor *d* for pressing the paddles *e* against the ring *b*.

In my device I use hollow paddles instead of the usual solid paddles and preferably of the type illustrated in detail in Figs. 3 to 5 and having a series of drilled holes *e*⁰.

55 As shown particularly in Fig. 3, each paddle is provided with a chamfer on the part thereof which rubs along the ring *b*, for the purpose of diminishing the contact surface with said ring and consequently a diminution in the wear of the said paddles as well as the said ring.

I provide each paddle with a sort of semi-cylindrical boss *e*¹ adapted to slide in a corresponding semicylindrical groove *d*⁰⁰⁰. I provide in ring *b* a sort of cavity *b*⁰⁰.

60 The purpose of this arrangement will be obvious to those skilled in the art as the increase in pressure which takes place behind the paddle becomes effective at the moment when the paddle rides over the cavity *b*⁰⁰ and acts on the boss *e*¹ which plays the part of a small piston exerting thereon a force opposed to the action of the springs *f* and substantially eliminates the friction of the paddles on the plates *c* whereby wear is prevented and constant tightness of the system assured.

65 With a view to producing good operation of my device I place the inner face of the bosses *e*¹ in communication with the atmosphere by means of suitable channels drilled in the rotor as shown at *e*² in Fig. 12.

Likewise I may provide my improved pump with suitable auxiliary packing means.

85 The rotor *d* is mounted in the stator *a* by any means well known in the art such as bearings.

I preferably have recourse to a device for regulating the operation or output of the 90 pump which consists in providing an outlet in the outlet conduit, which outlet is controlled by an arrangement which will now be described with reference to Fig. 14.

95 As shown in the figure *g* indicates a small piston-plug normally closing an escape conduit *h* connected at any convenient spot to the outlet conduit *h*¹ of the pump. The movement of this piston *g* is opposed by the action of a spring *i* provided with suitable adjusting 100

means not shown. From the foregoing it will be obvious that the piston *g* and the spring *i* being regulated to balance a certain delivery pressure, as soon as said pressure is surpassed the piston is raised and allows a certain quantity of the delivered fluid to pass out until the desired pressure is re-established.

The operation of my improved pump will be obvious from the nature of the foregoing description.

A pump constructed in this manner is extremely silent, has a constant output which is uniform, is of an extremely low net cost since it is machined, very easy to assemble and take apart and necessitates an upkeep which is practically nothing.

Adverting to Figs. 10 to 13, it will be noted that the volumes of the solid part and the hollow parts of the paddles are absolutely equal and that the fluid, particularly when said fluid is a liquid, circulates within the paddles which are extremely light and their stroke always takes place without shock.

The springs only act partially and the paddle is constantly braked by the liquid. In fact the said springs only act during coincidence of the chamfer of the paddles with the bevelled rear portion of the plates *c*. At this instant the liquid is able to become interposed between the paddle and the plate and is driven to the bottom of the paddle slot.

The bosses *e*¹ acting as small pistons yield under the pressure existing in the delivery zones in front of the paddles and separate them from the ring *b* in order to clear the plates *e* without friction.

While I have disclosed what I deem to be the preferred form of my device I do not wish to be limited thereto as there might be various changes made in the construction and arrangement of the parts without departing from the spirit of my invention as comprehended within the scope of the appended claims.

Having described my invention what I claim as new and desire to secure by Letters Patent is:

1. In a pump of the type described having a stator, the combination of a rotor concentrically disposed within said stator having a diameter smaller than said stator, a plurality of pairs of inlet and outlet conduits disposed in pairs, opening into the space existing between said rotor and said stator, a plurality of radially disposed slidably mounted paddles carried by said rotor adapted to contact with said stator, a plurality of cut-off plates carried by said stator contacting with said rotor for successively pushing said paddles into said rotor when passing from an inlet conduit to an outlet conduit, there being a pressure retaining recess formed in said stator around each of said outlet conduits and a projection carried by each of said paddles adapted to slide in a groove formed

in said rotor opening into the space there-around whereby said paddles are slightly raised by the pressure developed in said pump when passing over said plates and friction reduced.

2. Pump as in claim 1 wherein the paddles are hollow the volume of the solid parts of said paddles being equal to the volume of the hollows in said paddles whereby the paddles are balanced substantially as described.

3. Pump as in claim 1 wherein the interiors of the grooves in which the bosses of the paddles slide are put in communication with the atmosphere by means of channels formed in the rotor substantially as described.

In testimony whereof I hereunto affix my signature.

CASIMIR WRONA.
